UNITED STATES PATENT OFFICE.

MUGENT H. SLAUGHTER, OF MOUNTAIN LAKES, NEW JERSEY, ASSIGNEE TO WESTERN ELECTRIC COMPANY, INCORPORATED, OF NEW YORK, N. Y., A CORPORATION OF NEW YORK.

RADIO RECEIVING CIRCUIT.

Application filed September 6, 1924. Serial No. 736,941.

This invention relates to radio receiving circuits and has for its principal object to provide a receiving set all variable elements of which are capable of adjustment for reception of waves of different lengths by means of a single control element.

Another object of this invention is to provide a receiving set adapted to be used with various aerials without changing the dial settings.

10 A further object is to provide, in a receiving set, that the natural period of a tuned antenna circuit is not materially altered by a change in aerials.

15 A still further object is to increase the sharpness of tuning of the circuit.

Other objects and advantages will be apparent from the following specification and claims.

20 These objects are accomplished by means of a small condenser inserted between the aerial and tuned primary circuit constituting a selective element of the receiver.

Figs. 1, 2 and 3 show diagrammatically, 25 circuits embodying the invention in which corresponding parts are designated by the same reference numerals.

In all figures, condenser 1 is interposed between the aerial and primary circuit 2 which 30 may be tuned by variable condenser 16. The maximum capacity of the condenser 1 is of the order of 75 mmf. which is small compared to that of the other condensers or elements of the circuit involving capacity such as the aerial-to-ground capacity and condenser 16 in the 35 primary circuit 2, which would be of the order of 500 mmf. The condenser 1 may be as small as 50 mmf. it being understood that the values herein assigned are in an apparatus suitable 40 for receiving present broadcast messages on wave lengths of from 200 to 600 meters and that the values for other wave lengths will differ accordingly.

A secondary circuit 3 consisting of inductance 11 and secondary tuning condenser 12 45 is tuned to the same frequency as the circuit 2 and is loosely coupled thereto either by electromagnetic or electrostatic means which may be made variable, if desired, for the purpose of adjusting the coupling between the 50 circuits 2 and 3.

As indicated on the drawings, the condensers 12 and 16 are to be varied simultaneously by a single control element and in order to

effect this result it is needful that they be shunted during the tuning operation by effective capacities of equal value. The condensers 12 and 16 may, in general, be of any variable type, each being identical in design with the other.

Various means of coupling the primary and secondary circuits are shown in Figs. 1, 2 and 3. In Fig. 1, a series capacity coupling is obtained by condenser 7 which is preferably variable. In Fig. 2, a shunt capacity coupling is shown by means of condenser 8 between primary circuit 2 and secondary circuit 3. In Fig. 3, primary circuit 2 is coupled to secondary circuit 3 by receiving transformer 9 which may be made adjustable for varying the coupling. Any other means of coupling the circuits may be used without departing from the spirit of the invention.

A vacuum tube detector 4, provided with the usual stopping condenser shunted by a high resistance in the grid circuit, is connected across the circuit 3. The anode circuit 5 contains a telephone receiver 6 which typifies any desired receiving apparatus.

A small adjustable condenser 10 is connected in parallel to the secondary tuning condenser. The condenser 10 is adjusted so that the combined capacity of condenser 10, input capacity of vacuum tube 4, and distributed capacity of the secondary coil 11 and 85 the wiring is of the order of 50 mmf.

A single or plural stage amplifier may be inserted in tandem between the tube 4 and receiver 5 in any one of several well known manners, in which case the input capacity of 90 the amplifier is taken into account in the same manner as that of the detector when there is no amplifier.

The operation and advantages of this circuit may be explained as follows: The primary circuit contains capacity due to the tuning condenser and also due to the aerial, operating as two capacities in parallel. The secondary circuit has two capacities in parallel in a similar manner due to the secondary 100 tuning condenser and distributed capacity of coils, wiring and tube. In order to permit equal variation of both primary and secondary tuning condensers so that tuning can be effectively accomplished by varying them 105 by a single control without redesigning for each slightly different aerial, the effective values of the capacities in shunt must be made

equal. This was previously difficult of accomplishment as the aerial-to-ground capacity was varied each time the set was used on different aerials and was of a large magnitude 5 relative to the distributed capacity in the secondary circuit.

In accordance with this invention, the secondary capacity is adjusted to any desired amount by a small condenser 10 in parallel 10 to the tuning condenser. This condenser is adjusted so that the combined capacity resulting from the vacuum tube wiring and condenser itself is approximately 50 mmf., an amount large enough to permit of accurate 15 adjustment and sufficiently small so that the minimum capacity of the secondary circuit may be made as small as desired in tuning.

The primary is adjusted in an analogous 20 manner by inserting a condenser 1 of 75 mmf. maximum capacity in series with the aerial. By varying this condenser, the effective capacity of the aerial to ground and condenser 1 in series may be made any desired amount less than 75 mmf., the maximum capacity of 25 condenser 1. This will be the case irrespective of the type of aerial used.

If this capacity is made equal to the minimum secondary capacity or about 50 mmf. the primary and secondary tuning condensers 30 may be varied simultaneously by the same control means and the circuits will always be tuned to the same frequency.

Should the distributed capacity of the secondary circuit be 50 mmf. or greater, condenser 10 may be omitted. In case this capacity should be greater than 75 mmf. condenser 1 must have a larger maximum capacity to properly balance the circuits. It should be understood that the values herein 40 used are only examples. The actual values of condensers 1 and 10 must be determined in accordance with the particular type of receivers and the use to which it is to be put.

In practice, the small condenser 10 may be 45 adjusted in the factory and both tuning condensers connected to the same knob and dial. The set is then connected to an aerial and maximum signal strength obtained by adjusting condenser 1. After this is once adjusted for a given aerial, it will not thereafter need to be changed as the circuits are then of equal capacity and the single control knob will tune in all signals within the range of the receiver.

Condenser 1 also materially increases the 55 sharpness of tuning of the primary circuit as the loose coupling between the aerial and primary circuit caused thereby greatly reduces the damping effect of the aerial resistance on the primary circuit.

It is known that condensers have been used 60 in series with the aerial for purposes of tuning, but the instruments and purpose are considered to be entirely different than as herein set forth. The condenser 1 is too small to be

of any value in tuning and, in fact, would not vary the period of the aerial to ground circuit to any appreciable extent. Condensers such as previously used in tuning were so large that they could not function in accordance with this invention. They were not of sufficiently high impedance to insure absence of interaction between the aerial and tuned primary. The tuning of the primary was affected by the size of the aerial and the 75 sharpness of tuning was affected by the resistance of the aerial.

Although shown as applied to particular circuits it is to be understood that the invention is not limited in its application to 80 these particular circuits but only in accordance with the spirit of the invention as defined in the claims.

What is claimed is:

1. In a radio receiving circuit comprising 85 an aerial and tuning means, a condenser of the order of 75 mmf. interposed between said aerial and said tuning means to minimize the effect of the aerial on the tuning of the antenna circuit and a resonant circuit coupled 90 to said tuning means having a total minimum capacity substantially equal to the combined capacity of said aerial and said condenser.

2. In combination, two resonant circuits, 95 an element having capacity to ground, means for tuning both said circuits in a single operation, and a path between said element and one of said circuits including a capacity for minimizing the effect of said capacity to 100 ground on said circuits.

3. In combination, two coupled resonant 105 circuits, means for tuning said circuits in one operation, an element having capacity to ground connected to one of said circuits, another element having material capacity connected to the other of said circuits, and supplementary means associated with the circuit having capacity to ground for equalizing the 110 capacity of said elements whereby said circuits may be maintained in resonance at the same frequency.

4. In combination two coupled resonant 115 circuits, means for tuning said circuits in one operation, one of said circuits including an element having material inherent capacity and the other of said circuits being adapted to be connected to any one of several elements having different material capacities, and means to reduce the influence of said elements of different capacities on the tuning of the connected circuit comprising an additional capacity adapted to be included in the connection to said elements of different capacities.

5. In a radio receiving circuit comprising 120 an aerial and primary and secondary tuning means, means comprising a small condenser connected across said secondary tuning means to adjust the minimum secondary ca- 130

pacity to a finite value and means comprising a small condenser connected between the aerial and primary tuning means to adjust the antenna capacity to the same finite value so that equal changes in the primary and secondary tuning means will produce equal

cuits whereby they may be controlled by a single means.

In witness whereof, I hereunto subscribe my name this 5th day of September, A. D. 1924.

NUGENT H. SLAUGHTER.
